US00D993559S

(12) **United States Design Patent** (10) Patent No.: **US D993,559 S**
(45) Date of Patent: **** Jul. 25, 2023**

(54) **BATTERY PACK FOR POWER HEAD OF CANISTER VACUUM CLEANER**

(71) Applicant: **Marcus Cleff**, Cologne (DE)

(72) Inventor: **Marcus Cleff**, Cologne (DE)

(73) Assignee: **WESSEL—WERK GMBH**,
Reichshof-Wilbergerhuette (DE)

(**) Term: **15 Years**

(21) Appl. No.: **29/757,688**

(22) Filed: **Nov. 9, 2020**

Related U.S. Application Data

(63) Continuation of application No. 16/864,202, filed on May 1, 2020, now Pat. No. 11,399,683.

CLAIM

The ornamental design for a battery pack for power head of canister vacuum cleaner, as shown and described.

DESCRIPTION

FIG. 1 is a perspective end view of the invention; FIG. 2 is a small-scale side view of the invention; FIG. 3 is another side view of the invention; FIG. 4 is an opposite side view of the invention; FIG. 5 is a large-scale end view of the invention; and, FIG. 6 is an opposite large-scale end view of the invention. In the drawing a suction pipe and nozzle assembly are shown in broken lines to illustrate environment of use and are not part of the claimed design.
